Inventor,

H. Bartholomew

United States Patent Office.

H. BARTHOLOMEW, OF DOVER CENTRE, OHIO.

Letters Patent No. 69,961, dated October 22, 1867.

IMPROVEMENT IN FENCE.

The Schedule referred to in these Letters Patent and making part of the same.

TO ALL WHOM IT MAY CONCERN:

Be it known that I, H. BARTHOLOMEW, of Dover Centre, in the county of Cuyahoga, and State of Ohio, have invented certain new and useful improvements in Farm-Fences; and I do hereby declare that the following is a full and complete description of the same, reference being had to the accompanying drawings making a part of this specification, in which—

Figure 1 is a side view of the fence.

Figure 2 is an end view.

Figure 3 is a fence corner.

Like letters of reference refer to like parts in the views.

In fig. 1, A represents a fence-panel, which is constructed of four or more boards, B, nailed or otherwise secured to cross-pieces or cleats, C. These panels are supported and locked together by the posts D, fig. 2, which consists of a sill, E, and posts F, stayed by the braces G, and secured at the top by the cleat H. The posts F, referred to, are placed so far apart as to allow the ends of the boards of the panel to be inserted between them, lapping by each other, as shown in fig. 1, and which are thus held from any lateral displacement. In order to prevent the panels from pulling apart endwise, a deep notch is cut in the end of a board or rail of each panel, and made to fit and hook upon the cleat H, as shown in fig. 1, in which figure H is the cleat, and H' the rails or bars in which the said notch is cut. By this device a strong, neat, and easy locking together of the panels is made, which can be put up and taken down with great facility. In order to turn square corners with this fence, a post, I, fig. 1, is made, as follows: Four pieces of boards, of the proper length and width for the post, are nailed together, forming a box, as shown in fig. 3. Before nailing them together, however, square notches, J, are cut in one edge of the boards, of the proper size to receive the end of the rails of the fence-panel. Now, on nailing them together, one side piece covers the notches cut in the other, and thus makes a mortise into which the ends of the rails are put, as shown in fig. 3, and thus a strong and inexpensive post is produced, and which can be used for turning corners of any degree of angle, or one such can be used alternately with the triangular post D on a line of straight fencing, and thus add to the cheapness and neat appearance of the fence.

What I claim as my improvement, and desire to secure by Letters Patent, is—

The special construction and arrangement of the herein-described fence, in the manner substantially as described.

H. BARTHOLOMEW.
